DESIGN FOR A DISPLAY STAND

Jesse E. Roach, New York, N. Y., assignor to The
5¢ Cup Inc. of New Jersey, Edgewater, N. J.

Application September 6, 1935, Serial No. 58,458

Term of patent 14 years

To all whom it may concern:

Be it known that I, Jesse E. Roach, a citizen of the United States, residing at New York, in the county of New York and State of New York, have invented a new, original, and ornamental Design for a Display Stand, of which the following is a specification, reference being had to the accompanying drawings, forming part thereof.

Figure 1 is a perspective view of the display stand, showing my design.

Figure 2 is a view thereof in rear elevation,
Figure 3 is a top plan view thereof,
Figure 4 is a view thereof in front elevation,
and

Figure 5 is a view thereof in side elevation.

I claim:

The ornamental design for a display stand, as shown.

JESSE E. ROACH.
